UNITED STATES PATENT OFFICE.

THOMAS S. BENNETT, OF PROVIDENCE, RHODE ISLAND, ASSIGNOR TO
ALBERT C. BECKEN, OF CHICAGO, ILLINOIS.

DESIGN FOR A BRACELET.

SPECIFICATION forming part of Design No. 34,019, dated February 5, 1901.

Application filed November 9, 1900. Serial No. 35,987. Term of patent 3½ years.

To all whom it may concern:

Be it known that I, THOMAS S. BENNETT, a citizen of the United States of America, and a resident of Providence, county of Providence, and State of Rhode Island, have invented and produced a new and original Design for Bracelets, of which the following is a specification.

My invention relates to bracelets and is illustrated in the accompanying drawings, in which—

Figure 1 is a perspective view of the bracelet entire, and Fig. 2 is a partial view showing the appearance in front elevation.

The bracelet consists of a series of outer links A and a series of inner links B, which are united to form a continuous band, as shown in Fig. 1. The outer links A are of

an S shape, while the inner links B are two short curves united by a central portion B². These links cross each other at their centers and meet at their ends, so that the bracelet takes the form of a band of united crosses the parts of which are differently curved.

The leading feature of my design consists of a band of united crosses, the elements of which crosses are differently curved.

What I claim is—

The design for a bracelet as herein shown and described.

Signed at Attleborough, Massachusetts, this 18th day of October, 1900.

THOMAS S. BENNETT.
